United States Patent Office

Des. 222,922

Patented Feb. 1, 1972

222,922

TV PROGRAM SELECTOR

Joseph A. Doumit, 109 N. Evangeline St.,
New Iberia, La. 70560

Filed Mar. 12, 1970, Ser. No. 21,874

Term of patent 14 years

Int. Cl. D10—05

U.S. Cl. D52—6

Fig. 1

Fig. 2

FIG. 1 is a top plan view of a TV program selector showing my new design; and

FIG. 2 is a right side elevational view of FIG. 1, the opposite side being identical.

The bottom portion not seen is substantially plain and unornamented.

I claim:

The ornamental design for a TV program selector, as shown and described.
